UNITED STATES PATENT OFFICE

GEORG CARL HEINRICH WICHMANN, OF LONDON, ENGLAND

PRINTING MACHINE AND PRESS

Application filed March 30, 1928, Serial No. 265,904, and in Great Britain April 14, 1927.

The present invention relates to improvements in cylinders used in printing machines or presses.

Hitherto cast iron cylinders have generally been used for this purpose. Each of these has to be cast specially, entailing either the maintenance of a large stock of different sizes, or delay in the execution of orders. Further such cylinders are heavy, liable to fracture, and subject to local weaknesses, such as blow-holes and inequalities of thickness, and it is a process of considerable difficulty to true them up.

I have found that an efficient cylinder can be constructed of a rolled metal shell with radial supports, preferably in the form of pressed out or rolled disks, the shell, supports and shafts being united by welding to form an integral structure, and that great advantages arise from the use of cylinders so formed, as will be hereinafter more fully described.

Reference is had to the accompanying drawings, in which like parts are indicated by similar reference symbols throughout the several views, and in which

Figure 1 is a side view of a cylinder provided with radial spokes, connected to the shell and shaft by welding,

Figure 2 shows a section on the line A—A of Figure 1, using a spoke construction,

Figures 3, 4 and 5 show plates or disks to be used as radial supports in lieu of the spoke construction.

Figure 6 is an end view of the left hand end of a plate cylinder using radial supports in the form of pressed metal disks.

Figure 7 is a similar view of the opposite end of the same cylinder.

Figure 8 is a plan view showing the complete cylinder of Figures 6 and 7 mounted on its shaft.

Referring first to Figures 1 and 2, on a shaft or spindle 1, are welded radial supports 2 which are given the form of arms or spiders, and arranged in radial sets spaced apart along the shaft, these arms or spiders being of rolled steel bar or rail welded to the shaft. The shaft may be of rolled steel and of solid or hollow section.

The cylinder drum is completed by wrapping a rolled steel plate or plates around the radial supports to form the cylinder shell or drum wall, and welding the plate or plates to the ends of the arms or spiders, and, if there are several plate sections, to each other.

Where necessary, the gap 3 is left for the reception of the gripping devices or clamping devices, depending on the particular form of cylinder being made. This gap may be conveniently provided by a segmental space left between radial sets of arms or spiders. The faces 4 of the arms or spiders forming the gap walls may be re-inforced by plates welded thereto, or the plate or plates forming the cylinder shell may be as shown folded over at 5 and welded to the arms or spiders.

Strengthening rings 7 may be welded or otherwise connected to the radial sets of arms or spiders.

Referring now to Figures 4 to 8, the radial arms 2, of Figures 1 and 2, are replaced by discs or plates of suitable section, in which gaps are cut if necessary for the insertion of gripping or other devices. Figures 3, 4 and 5 show, respectively, radial supports in the form of pressed steel discs or plates. The numeral 10 represents one of the end plates, 11 represents one of the intermediate plates, and 12 the center plate, these plates or discs being formed by pressing.

In Figures 6 to 8 inclusive, 1 represents the shaft, 6 the cylinder shell or drum wall, 10 the left side disc, 10^a the right side disc, 13 the reinforcing bars forming the gap walls, 14 and 14 lugs on which the ordinary gear wheels, not shown, are mounted.

For convenience in manufacture the cylinder shell or drum wall may be made up of circumferential sectional parts 6, the meeting ends of the multiple parts being welded to a common arm or disc, and the meeting edges being welded to each other. With such a method of manufacture the various welding operations can be effected with more ample space for the manipulation of the welding set, as the cylinder shell is gradually built up. But in any case the usual gapping enables the welding operations to be conveniently performed.

In all types of printing machine the lightness of the cylinder has a considerable effect on the speed at which the machine can be run, the power needed, and the strength required in the other portions of the machine, whilst in the case of a reciprocating cylinder the question of the weight, and consequently the momentum which has to be reversed at every revolution, is all important. At the approximate weight of, say a 26" cast-iron cylinder as used on one of the applicant's two colour machines, would be about one ton the importance of this can be realized. The invention therefore enables printing to be carried out at speeds heretofore unattainable.

By the use of the present invention a cylinder is supplied at low cost which is at least 50% lighter than cylinders of the type used in practice, and which has the further and important property of being uniform.

It is impossible to obtain from any foundry a printing cylinder cast in such a manner that the outer walls are uniform in thickness throughout the whole of their respective areas, still less the portions joining the outer walls to the axis, and to correct this want of truth, complicated scientific balancing becomes necessary, involving additions to the original cylinder, to enable such cylinder to be rotated or reciprocated without undue strain on the machine. The whole process of balancing is costly, involving, *inter alia*, the machining of the recesses in which the balance weights are placed.

Further such cast cylinders are heavy, liable to fracture, and subject to local weaknesses, such as blowholes. Owing to these defects the truing up of cast iron cylinders involves the removal of up to 3/8"—a preliminary process of turning in a lathe being frequently necessary before the ordinary machining is started, whereas with the steel cylinders, as herein described, a slight machining, removing about 5/1000" is all that is necessary.

In the steel cylinders, herein described, not only are the outer walls uniform, but the disks or other radial supports, being made out of pressed or rolled steel, are also uniform, rendering balancing unnecessary. There is thus produced, for the first time, a cylinder capable of use without any extraneous additions.

These cylinders also have very great strength, and a test has shown that, even when six times the ordinary maximum pressures required for printing has been applied to such a cylinder, no deformation whatever can be detected under the most careful tests.

Another very great advantage is that as no casting is involved the cylinders can be made with great rapidity, and it is therefore unnecessary to keep anything like the same stock of different sizes of cylinders as was necessary under the old system. All that is

necessary is to have a supply of standard sizes of rolled metal.

A cylinder made according to applicant's invention can be manufactured in about one sixth of the time involved in making a similar cylinder in cast iron.

Further advantages of a built-up cylinder are as follows:—

All cylinders of the same diameter can be built up from one set of standardized divisional plates and end walls, whatever their length or printing surface.

The outer coverings are of the same uniformity throughout, thereby entirely eliminating the possibility of blow holes, as experienced with cast iron bodies which, in certain instances, cannot even be detected in the finished cylinder.

All foundry work is dispensed with, and the necessity for making costly patterns is entirely eliminated.

Primarily, the very fact of having to manufacture suitable patterns for the preparation of cast iron cylinders is in itself an extremely expensive item, and taking into consideration the heavy abuse to which these are subjected, with standard foundry practice, the overhead charges with regard to repairs and renewals of the patterns is an important item.

The finished weight of rolled steel cylinders is about half that of cast iron.

Owing to the lighter weight of steel cylinders, the vibration ordinarily set up in machine when much heavier cast iron cylinders are used, is avoided to a great extent; therefore, through absence of vibration, machines built with built up welded steel cylinders are capable of being run at a much higher speed than those with cast iron cylinders.

Although lighter, cylinders made of rolled steel are in fact stronger, inasmuch as they are capable of withstanding heavier pressures.

Another very important advantage is that the risk of breakage through falls or rough handling, which is very considerable in the case of castings, is eliminated.

Figuring on the expense of manufacture, the producing and finishing of a cast cylinder ready for use will cost say 100 units. A cylinder made by the herein described invention will cost about 60 units.

Again, if the weight of the cast cylinder be 100 units, the weight of the welded cylinder will be about 50 units.

In addition to the saving in the production cost there is a saving in cost of freightage charges, the saving being due to the difference in the two weights.

I would have it to be understood that the term "printing machines" in the claims should be read as to include "printing presses."

What I claim is:—

1. A cylinder for use in printing machines

comprising a central shaft, a shell made of rolled metal curved to cylindrical shape concentric with said shaft, and radial supports for said shell securely mounted on said shaft
 5 and interposed between said shell and said shaft, said supports being welded to said shell to form an integral structure therewith.

2. A cylinder for use in printing machines comprising a central rolled metal shaft, a shell made of rolled metal curved to cylindrical shape concentric with said shaft, and radial supports for said shell mounted on said shaft and interposed between said shell and said shaft, said supports being welded to said shell and also to said shaft to form an integral structure.

3. A cylinder for use in printing machines comprising a hollow rolled metal central shaft, a shell made of comparatively thin rolled metal curved to cylindrical shape concentric with said shaft, and pressed metal radial supports for said shell mounted on said shaft and interposed between said shell and said shaft, said supports being welded to said shell and also to said shaft to form an integral structure.

4. A cylinder for use in printing machines comprising a central rolled metal shaft, a shell made of rolled metal curved to cylindrical shape concentric with said shaft and pressed metal discs forming radial supports for said shell mounted on said shaft and interposed between said shell and said shaft, said supports being welded both to said shell and to said shaft to form an integral structure therewith.

5. A cylinder for use in printing machines comprising a central shaft, a shell made of rolled metal curved to cylindrical shape concentric with said shaft, said shell being gapped longitudinally, and provided with reinforcing ribs at each side of the gap, and radial supports for said shell securely mounted on said shaft and interposed between said shell and said shaft, said supports being welded to said shell to form an integral structure therewith.

6. A cylinder for use in printing machines comprising a central shaft, a shell made of rolled metal curved to cylindrical shape concentric with said shaft, said shell being gapped longitudinally, and provided with reinforcing ribs at each side of the gap, and pressed metal discs forming radial supports for said shell and said shaft, said supports being welded to said shell to form an integral structure therewith.

7. A cylinder for use in printing machines comprising a central rolled metal shaft, a shell made of rolled metal curved to cylindrical shape concentric with said shaft, said shell being provided with longitudinal gaps with reinforcing ribs at each side of said gaps, and pressed metal discs forming radial supports for said shell mounted on said shaft, and in-

terposed between said shell and said shaft, said supports being welded to said shell and also to said shaft to form an integral structure.

In testimony whereof, I affix my signature. 70
 GEORG CARL HEINRICH WICHMANN.
